UNITED STATES PATENT OFFICE.

WILLIAM H. SYMONDS, OF ALLENDALE, NEW JERSEY, ASSIGNOR OF ONE-HALF TO
CAROLINE E. BRAINARD, OF NEW ROCHELLE, NEW YORK, AND ONE-HALF TO
IRENE V. SYMONDS, OF ALLENDALE, NEW JERSEY.

ACTUATING DEVICE FOR WINDOW SASHES, SHUTTERS, AND LIKE MOVABLE PARTS.

1,077,768.

Specification of Letters Patent.

Patented Nov. 4, 1913.

Application filed March 25, 1913. Serial No. 756,663.

To all whom it may concern:

Be it known that I, WILLIAM H. SYMONDS, a citizen of the United States, and a resident of Allendale, in the county of Bergen and State of New Jersey, have invented a new and Improved Actuating Device for Window Sashes, Shutters, and like Movable Parts, of which the following is a full, clear, and exact description.

10 The object of the invention is to provide a new and improved actuating device, more especially designed for conveniently opening and closing sashes of casement windows, shutters and the like, from the inside of a room and to securely lock the part in either open or closed position, and in order to accomplish the desired result, use is made of lazy tongs, pivotally connected at one end to the part to be opened or closed, a casing 15 mounted to swing on the window sill or other support and provided with a pivot on which the inner members of the lazy tongs are pivoted, an arm extending inwardly from one of the inner members of the lazy 20 tongs and a pivoted handle on the said arm for opening and closing the lazy tongs.

25 A practical embodiment of the invention is represented in the accompanying drawings forming a part of this specification, in which similar characters of reference indicate corresponding parts in all the views.

Figure 1 is a sectional plan view of a casement window provided with the improved actuating device, the cover of the casing being removed and the sash being shown in closed position; Fig. 2 is an enlarged cross section of the same on the line 2—2 of Fig. 1; Fig. 3 is a plan view of the actuating device as applied to a casement window shown 30 in section and the sash in open position; Fig. 4 is an elevation of the inner end of the casing; Fig. 5 is an enlarged perspective view of the inner end of the lazy tongs, the actuating handle and the covering plate; Fig. 6 is a perspective view of the base plate 35 for the casing to swing on; and Fig. 7 is a similar view of the attaching plate on the sash or other movable part.

40 On the top of the window sill A is secured a base plate B provided near its forward end with a pivot B' on which is mounted to swing the bottom C' of a casing C in which is arranged a pivot C' a distance inward from the pivot B'. On the pivot C' are

55 mounted to swing the inner members D' and D² of lazy tongs D having their outer members D³, D⁴ pivotally connected with a pivot E' held on an attaching plate E secured to the bottom rail of a window sash F connected by a hinge F' with the window casing G, 60 as is common in casement windows. The forward end C² of the casing C is open for the passage of the lazy tongs, as will be readily understood by reference to the drawings.

65 The inner member D' of the lazy tongs D is provided with an extension arm D⁵ passing through a slot C⁴ in the inner end of the casing C, and on the outer terminal of the arm D⁵ is pivoted a handle H adapted to be 70 taken hold of by the operator for opening or closing the lazy tongs D with a view to swing the sash F from a closed position into a partly or wholly open position, as indicated in Fig. 3, or to swing the sash back 75 into a closed position. The handle H when not in use for imparting a swinging motion to the arm D⁵ is swung upward onto the top of the casing, and the handle H is provided with an integral lug H' adapted to engage 80 one of a series of notches C' formed in the inner edge of the top plate C⁶ of the casing C to lock the handle H in position with a view to prevent the lazy tongs D from accidentally opening or closing. The handle H 85 when in extended position, as shown in Figs. 1 and 5, is unlocked to permit the operator to impart a sidewise movement to the handle with a view to swing the arm D⁵ from the right to the left or from the left to the right 90 with a view to open or close the lazy tongs D for the purpose above described. The pivotal end of the handle H is provided with a shoulder H² adapted to abut against and be guided on a segmental edge C' at the rear end of the bottom plate C'. On the extension arm D⁵ outside of the casing C is arranged a segmental cover plate I closing the slot C⁴ to prevent dust or other impurities from passing into the room from the 95 outside. In case a screen J is used on the window casing, such screen is provided at its bottom with a cut-out portion J' to accommodate the casing C as indicated in Figs. 1, 2 and 3. It is understood that when a 100 swinging motion is given to the handle H at the time the latter is in extended position, the casing C swings on its pivot B' to ac-

commodate itself to the opening or closing movement of the lazy tongs D and the sash F so that the lazy tongs extend at all times in proper position relative to the casing C.

5. The actuating device shown and described is very simple and durable in construction and composed of comparatively few parts, not liable easily to get out of order. By the use of the actuating device 10 the sash or other movable part can be readily swung into an open, closed or partly open position, and locked in the adjusted position, without the operator being required to open the screen J or bend out of the window, owing to the fact that the handle H can be readily manipulated by the operator within the room in which the window is located.

Having thus described my invention, I 20 claim as new and desire to secure by Letters Patent:—

1. An actuating device for sashes, shutters and like movable parts, comprising a casing mounted to turn, lazy tongs having their 25 outer members attached to the part to be actuated and having their inner members pivoted in the said casing, the said casing being arranged to contain the lazy tongs when the part to be actuated is in closed 30 position, and an actuating handle on one of the inner members of the lazy tongs.
2. An actuating device for sashes, shutters and like movable parts, comprising a casing mounted to turn, lazy tongs having their 35 outer members attached to the part to be actuated and having their inner members pivoted in the said casing, the casing being adapted to contain the lazy tongs when the part to be actuated is in closed position, one 40 of the inner members of the lazy tongs having an extension arm extending through a slot in the casing to the outside thereof, and a handle on the outer end of the said extension arm.

45. 3. An actuating device for sashes, shutters and like movable parts, comprising a casing mounted to turn, lazy tongs having their outer members attached to the part to be actuated and having their inner members 50 pivoted in the said casing, one of the inner members having an extension arm and the casing having a slot through which extends the said arm to the outside of the casing, and a handle pivoted on the outer end of the 55 said extension arm, the said casing having a series of notches adapted to be engaged by the said handle.

4. An actuating device for sashes, shutters and like movable parts, comprising a casing 60 mounted to turn, lazy tongs having their outer members attached to the part to be actuated and having their inner members pivoted in the said casing, one of the inner members having an extension arm and the 65 casing having a slot through which extends

the said arm to the outside of the casing, a covering plate on the said extension arm covering the said slot, and a handle pivoted on the outer end of the said extension arm, the said casing being provided with notches 70 adapted to be engaged by the said handle.

5. An actuating device for sashes, shutters and like movable parts, comprising a plate adapted to be attached to a window sill and provided at its forward end with a pivot, 75 a casing mounted to turn on the said pivot and provided at its outer and inner ends with slots, the casing being provided with a top plate having notches along its inner edge, a pivot in the casing a distance rearwardly from the said plate pivot, lazy tongs 80 extending through the outer casing slot and having their outer ends pivotally connected with the part to be actuated, the inner members of the lazy tongs being pivoted on the 85 said casing pivot, and one of the inner members being provided with an extension arm passing through the inner casing slot, and a handle pivoted on the terminal of the said arm and provided with a lug adapted to engage one of the said notches in the casing.

6. An actuating device for sashes, shutters and like movable parts, comprising a plate, adapted to be attached to a window sill, and provided at its forward end with 90 a pivot, a casing mounted to turn on the said pivot and provided at its outer and inner ends with slots, the casing being provided with a top plate having notches along its inner edge, a pivot in the casing a distance rearwardly from the said plate pivot, lazy tongs 95 extending through the outer casing slot and having their outer ends pivotally connected with the part to be actuated, the inner members of the lazy tongs being pivoted on the 100 said casing pivot and one of the inner members being provided with an extension arm passing through the inner casing slot, a segmental cover plate 105 on the extension arm outside of the casing 110 and closing the inner casing slot, and a handle pivoted on the terminal of the said arm and provided with a lug adapted to engage one of the said notches in the casing, the said handle having a shoulder at its 115 pivoted end and the said casing having a segmental edge against which is adapted to abut the said shoulder.

7. An actuating device for sashes, shutters and like movable parts, comprising a fixed 120 base plate provided with a pivot, a casing mounted to swing on said pivot, lazy tongs having their outer members attached to the part to be actuated and having their inner members pivoted in the said casing, and actuating means connected with one of the inner members of the lazy tongs.

8. An actuating device for sashes, shutters and like movable parts, comprising a support, 125 a casing mounted to turn on said sup- 130

port, lazy tongs, means for pivotally connecting the outer members of the lazy tongs to the part to be actuated, a pivot in the casing on which the inner members of the 5 lazy tongs are mounted to swing, the said lazy tongs being folded within the casing when the part to be actuated is in closed position, an actuating handle pivotally connected with one of the inner members of the 10 lazy tongs and adapted when moved sidewise to open or close the lazy tongs, and means for preventing accidental sidewise movement of the said handle.

9. An actuating device for sashes, shutters 15 and like movable parts, comprising a base plate adapted to be secured to the top of a window sill, and provided near its forward end with a pivot, a casing having its bottom plate mounted to swing on said pivot, 20 lazy tongs having their outer members attached to the part to be actuated and having their inner members pivoted in the said

casing, the casing having its outer end open for the passage of the lazy tongs, one of the inner members of the lazy tongs having an 25 arm extending through a slot in the inner end of the casing, a handle member pivoted to said arm outside the casing and adapted when in the extended position to be moved sidewise to swing the arm to open or close 30 the lazy tongs, the said handle member when not in use being adapted to be swung upward onto the top of the casing, and means for preventing accidental sidewise movement of the handle member when in the lat- 35 ter position.

In testimony whereof I have signed my name to this specification in the presence of two subscribing witnesses.

WILLIAM H. SYMONDS.
